UNITED STATES PATENT OFFICE.

ALBERT W. METZNER, OF DAYTON, OHIO, ASSIGNOR TO JOHN Q. SHERMAN, OF DAYTON, OHIO.

PRINTING PRESS.

Application filed December 27, 1921. Serial No. 524,896.

To all whom it may concern:

Be it known that I, ALBERT W. METZNER, a citizen of the United States, and a resident of Dayton, in the county of Montgomery and State of Ohio, have invented certain new and useful Improvements in Printing Presses, of which the following is a full, clear, and exact description, reference being had to the accompanying drawings, forming part of this specification.

My invention relates to printing presses and more particularly to presses used in the printing of manifolding paper, or other ruled line, blank form paper, in which it is desirable that uniform position of printed matter on webs of paper be accurately maintained at all times. It also relates more particularly to printed form machines, which employ continuous webs of paper.

Referring more particularly to the printing of manifolding forms by which is meant a plural series of the same form adapted to be superimposed for the purpose of making carbon copies or other forms of transferred copies. In such printing the misalignment of printed matter on forms that are later to be placed together will result in an improper placing on the under sheets of the transferred marks made on the topmost or master sheet.

The usual method of printing manifolding forms is to run a wide web of paper through a printing press, and to print cross-wise of the sheet the desired number of forms, usually three. These forms must correspond exactly, as has been stated, and this correspondence should be not only with relation to the longitudinal placing of the printed matter on the paper, but also to the lateral placing. The webs are later split up into three (in this instance) separate webs, and are fed or placed together in a manifolding machine, or pad, or the like, so that the close correspondence of the side edges of the forms or aligning holes in the forms to the printed matter is of considerable consequence.

While presses of any type are adjustable and great precaution may be exercised in the operation of such presses, still I have found that without some accurate guide which can be continuously observed by the press man, there is likely to occur a considerable accumulation of error before it can be observed and corrected.

In printing presses where wide webs of paper are printed upon, as above noted, thus providing space for printing several plates, it is important that all of these plates align with each other, and that they be absolutely parallel with the press, and also that the press operates only a certain specific distance each time, as may be specified, and for which the press has been set. The number of forms necessary to fill in the wide printing web are locked up in a chase and any slight shifting about of the plates in the chase must be corrected at once to avoid wider shifting and, as has been noted, accumulation of error.

It is the object of my invention to apply to the paper coming from a press, more particularly of the special kind noted, a straight edge which will be adjustable to or utilizable with different pieces of work, and will provide an accurate guide for the operator.

In manifolding paper, of a certain type, there are holes punched in the forms for subsequent engagement with feeding and aligning pins, and the spacing of these holes and the position of them on the forms must also be closely watched by the operator. My device I also use for this purpose, and for this reason, in the drawings, I show it as applied to the forms after they have been both printed and punched.

I accomplish the above objects and other advantages to be noted by that certain construction and arrangement of parts to be hereinafter more specifically pointed out and claimed.

In the drawings, Figure 1 is a perspective view of the end of a manifolding paper printing press, showing my invention applied thereto.

Figure 2 is a front elevation of my device. Figure 3 is a plan view illustrating the straight edge by itself lying over a web of paper.

The press is merely indicated by the frame 1, over which passes a web of paper which has been printed into two like forms cross-wise thereof, as shown at A and B.

After passing to the forward or delivery end of the machine, the paper web runs over a guard and idler roll device 2 and thence is wound up on a drum 3.

My new device is shown as mounted over the end of the press frame, so that the paper passes beneath it, and is erected on stand-

ards 4, 4, accurately mounted at the sides of the bed.

These standards are braced together by a rod 5 in the special device shown in the drawings, and carry a revoluble shaft 6 from which the straight edge is suspended. This shaft is controlled in its position by a finger piece or wheel 7 mounted on its end, and one or both of the standards carries a set 10 screw 8 which screws into the shaft and locks it in desired positions in the standards.

From the shaft depend the desired number of arms 9, in the lower ends of which is rotatably mounted a shaft 10. This shaft 10 is intended to rock freely in the arms 9 so as to permit the straight edge to maintain an even "keel" at all positions of adjustment.

20 The straight edge 11 is mounted on the shaft 10 by means of arms 12 set fast on both elements 10 and 11, and underneath the knife, as a convenient form of rest, I may mount knobs 13, which will lie on the paper supporting guard 2 at the end of the press.

It will be observed that I have merely attempted to describe above one convenient and simple form of mounting for a straight edge, and that the exact construction and 30 position over the forms issuing from a press must be altered to suit various conditions.

As a special form of straight edge adaptable for use with a multiple width printing press for manifolding paper, I show 35 in Figure 3 the straight edge 11 having graduations of a scale thereon and bearing slidably a number of arrow indicator devices. Thus there are bands 14 around the straight edge, which bands are slidable 40 thereon and carry small set screws 14^a at the rear end, which bear on the back of the straight edge. On the forward end these bands carry pointers 15 which come down into close proximity with the paper.

45 Describing the operation of my invention as applied to manifolding paper, it will be noted that when a press run is started, the paper is run through it until it comes printed and, if desired, punched as at 15^a under the straight edge. The operator then places the straight edge by freeing and revolving the upper shaft in its journals in the standards until the edge lies along some 50 convenient cross line in the printing. If, 55 upon doing this, it is discovered that the cross line does not form an exact right angle direction to the press, the press is reset until it does so.

60 The adjustable arrow pieces are then slid along until they point, say, to the dividing lines 16 printed between the three sets of forms A, B and C. They are then locked in place, after it has been determined if there is a proper spacing of these dividing 65 lines, as per the notations on the scale.

The press man may then start his press and watch the straight edge and pointers to see that the operation remains perfect. The adjustability of the straight edge enables him to bring some printed line or other mark 70 on the paper in exact correspondence with the guiding edge and the fact that the edge indicates a certain line on the form enables the operator to tell if an intermittently feeding press is issuing the correct length of 75 form.

The even keel of the straight edge is maintained by the knobs on the ends resting on some sort of bed or support, and by the pivotal mounting of the blade on the lower ends 80 of the arms. The body of the straight edge may take different angles, but the guiding edge thereof will always be close to the paper, thereby avoiding parallax.

Having thus described my invention, what 85 I claim as new and desire to secure by Letters Patent, is:—

1. In combination with a printing press adapted to print and feed a portion of paper, a straight edge mounted in desired alignment across the path of the paper as it comes from the press, whereby the alignment of the printing on the paper may be observed.

2. In combination with a printing press 95 adapted to print and feed a portion of paper, a straight edge mounted in desired alignment across the path of the paper as it comes from the press, whereby the alignment of the printing on the paper may be observed, 100 said straight edge being adjustable lengthwise of the paper path.

3. In combination with a printing press adapted to print and feed a portion of paper, a straight edge mounted in desired alignment across the path of the paper as it comes from the press, whereby the alignment of the printing on the paper may be observed, and indicator members mounted 105 on the straight edge to provide a guiding mark lengthwise of the path of the paper.

4. In combination with a printing press adapted to print and feed a portion of paper, a straight edge mounted in desired alignment across the path of the paper as it comes from the press, and means for supporting said straight edge with its guiding edge in close proximity but out of contact with the paper, whereby parallax is avoided and the alignment of the printing on the 110 paper may be observed.

5. In combination with a printing press adapted to print and feed a portion of paper, a straight edge mounted in desired alignment across the path of the paper as it comes from the press, whereby the alignment of the printing on the paper may be observed, and adjustable indicator members mounted on the straight edge to provide a guiding 115 mark lengthwise of the path of the paper.

6. In combination with a printing press adapted to print and feed a portion of paper, a straight edge mounted in desired alignment across the path of the paper as it comes 5 from the press, whereby the alignment of the printing on the paper may be observed, said straight edge being adjustable lengthwise of the paper path, and adjustable indicator members mounted on the straight edge 10 to provide a guiding mark lengthwise of the path of the paper.
7. In combination with a printing press adapted to print and feed a portion of paper, a guide for observing the proper press operation and alignment of plates in a chase or 15 the like, comprising components having a superimposed coincidence both lengthwise and crosswise of the path of the paper.
8. In combination with a printing press 20 adapted to print and feed a portion of paper, a guide for observing the proper press operation and alignment of plates in a chase or the like, comprising components having a superimposed coincidence both lengthwise
- and crosswise of the path of the paper, said 25 components being adjustable to a variety of fixed positions.
9. In combination with a printing press adapted to print and feed a length of paper, a straight edge device comprising standards 30 extending above the path of the paper, a support adjustable in said standards, and a straight edged element suspended from said support so that its edge will depend to a position of proximity to the paper. 35
10. In combination with a printing press adapted to print and feed a length of paper, a straight edge device comprising standards extending above the path of the paper, a shaft revoluble in said standards, means to 40 hold the shaft in desired rocked position in the standards, and a hanger device on said shaft and a straight edged member pivotally swung from said hanger, whereby the edge of said member will depend in all positions of the hanger device into a position 45 adjacent to the paper.

ALBERT W. METZNER.
